UNITED STATES PATENT OFFICE.

JULIAN F. DRAKE, OF TRACY, MINNESOTA, ASSIGNOR OF ONE-HALF TO
JOSEPH KEMNA, OF GHENT, MINNESOTA.

DETACHABLE BOILER-FLUE.

No. 841,381.

Specification of Letters Patent.

Patented Jan. 15, 1907.

Application filed October 4, 1906. Serial No. 337,335.

To all whom it may concern:

Be it known that I, JULIAN F. DRAKE, of Tracy, county of Lyon, State of Minnesota, have invented certain new and useful Improvements in Detachable Boiler-Flues, of which the following is a specification.

My invention relates to detachable boiler-flues, and has for its object to improve the device shown and described in Letters Patent of the United States, No. 698,471, issued to me April 28, 1902.

My invention consists generally in various constructions and combinations, all as hereinafter described, and particularly pointed out in the claims.

In the accompanying drawings, forming part of this specification, Figure 1 is a view partially in section and partially in plan, illustrating the application of my invention to a boiler-flue and flue-sheet. Fig. 2 is a similar view illustrating a slightly-modified construction. Fig. 3 is a front view.

In the drawings, 2 represents the flue-sheets, having flue-seats 3, that are tapered slightly in the same direction—that is, the flue-seat on the left flares slightly from its outer toward its inner end and the corresponding seat in the opposite sheet flares in a similar manner from its inner toward its outer end.

4 is a tapered or conical sleeve provided at one end of the flue and fitting within the seat 3 and tapered from its outer toward its inner end and brazed or otherwise secured to one end of a flue 5. A packing-ring 6, of copper or other material that is comparatively soft and fusible at a high temperature, is fitted between the sleeve 4 and the seat 3, the outer end 7 of the packing-ring being upset, as indicated in the figure, and the middle portion of the ring fitting snugly against the tapered flue-seat and forming a tight joint therewith. At the opposite end of the flue a tapered sleeve 8 is provided, loose or brazed on the flue, as preferred, and between this sleeve and the flue-seat is a ring corresponding to the packing-ring described and having the same functions, but with its inner end upset, as indicated, instead of its outer end. The end of the flue is threaded, as indicated at 9, and a lock-nut 10 is provided thereon, having a recessed or annular groove 11 in its inner face, wherein a packing material 12 is

located and adapted to be forced against the ends of the flue 8 and its sleeve and packing-ring when the nut is tightened. Seats 13 are provided in the nut to receive the pins of a wrench whenever it is desired to tighten or loosen the flue.

In Fig. 2 a similar construction is employed, except that both ends of the flue are threaded and the sleeve 14 at one end is internally threaded to fit the flue and tapered to correspond with the seat of the flue in the sheet. A similar sleeve 15 is provided at the opposite end of the flue, packing-rings being provided between the sleeve and sheets, as shown. A lock-nut 16 engages the outer face of the flue-sheet and when tightened draws the flue therethrough and forces the tapered sleeves into the seats in the flue and locks the flue and sheets securely together, though permitting them to be separated whenever desired. The rings 14 and 15 will contain sufficient stock to allow for the formation of the threads thereon, and their ends will be provided, preferably, with seats or sockets corresponding to those in the nut 10 for convenience of adjustment of the rings on the flue.

I claim as my invention—

1. In a boiler, the combination, with the flue-sheets spaced apart and in parallel relation with one another and having tapered flue-seats extending therethrough from one side to the other, said seats being tapered in the same direction, one from the inner toward the outer surface of its sheet and the other from the outer toward the inner surface of its sheet, a flue extending through said sheets, and having a threaded end, tapered sleeves provided on said flue and fitting within said seats, said sleeves being tapered to correspond with said seats, packing-rings interposed between said sleeves and seats and a lock-nut provided on the threaded end of said flue and whereby said sleeves and rings may be drawn snugly against said seats.

2. In a boiler, the combination, with the two flue-sheets having tapered flue-seats, of a flue extending through said sheets and having a threaded end, conical sleeves inclosing said flue and having tapered exterior surfaces corresponding to the taper of said seats, one of said sleeves being rigidly secured on said flue and the other being screw-threaded thereon, packing-rings of relatively soft material

interposed between said sleeves and seats, and a lock-nut provided on the threaded end of said flue for the purpose specified.

3. The combination, with the flue-sheets having the tapered flue-seats, of a flue extending therethrough, sleeves inclosing said flue and having exterior surfaces tapered to correspond with the taper of said seats, packing-rings of comparatively soft material interposed between said sleeves and sheets, and a lock-nut provided on the threaded end of

said flue and having a countersunk inner face and a packing-ring fitting within said countersunk face and bearing on the outer ends of the contiguous sleeve and packing-ring, substantially as described. 15

In witness whereof I have hereunto set my hand this 29th day of September, 1906.

JULIAN F. DRAKE.
